UNITED STATES PATENT OFFICE.

HARRY D. HAMPTON, OF FRESNO, CALIFORNIA, ASSIGNOR OF ONE-SIXTH TO OSCAR BOWMAN, OF FRESNO, CALIFORNIA.

ROTARY DRILL.

1,192,419.

Specification of Letters Patent. Patented July 25, 1916.

Application filed July 12, 1915. Serial No. 39,293.

To all whom it may concern:

Be it known that I, HARRY DONALD HAMPTON, a citizen of the United States, residing at Fresno, in the county of Fresno, State of California, have invented certain new Improvements in Rotary Drills.

The following is a full, clear, and exact description of the same, such as will enable others, skilled in the art to which it applies, to make and use the same, reference being had to the accompanying drawings, for a better comprehension thereof, which form a part of this specification.

My invention relates to a rotary drill.

My object is to so construct a bit of such novel leverage parts and connections, so mounted on a suitable cylindrical shaft or stem with bits attached, that the entire mechanism can be lowered, preferably by cable, through a drill pipe or tube, to a specially constructed shell or retainer at the bottom of the pipe thereof; and, by action of its levers and parts, the blades of the bit will be expanded to a set width, and be locked securely. Or, when desired this bit and mechanism may be removed from its special retainer or shell by attachment of cable, and drawn up and out of drill pipe, for the purpose of renewal or sharpening; thus causing a great saving in time over existing methods, whereby it is necessary in order to change bits, to remove the entire drill pipe from the well, or other holes being sunk, unscrewing the same into short lengths at great loss of time. This great economy, I accomplish by the peculiar construction, novel combination, and adaptation of parts, hereinafter particularly described, and specifically pointed out in the claims hereunto annexed, reference being had to the accompanying drawings, in which the stem or shaft with its levers, connection and blades are shown in their various positions of action and working relations.

Figure 1 shows the stem, with blades of bit collapsed, and position of center blade, when bit is in readiness to be lowered or raised through the drill pipe. Fig. 2 shows an outline of the drill shell or retainer, with all parts of bit in place, ready for drilling. Fig. 3 is the same as Fig. 2, excepting that a portion of the shell or retainer is removed, showing a portion of the structure by which the blades of the bit are adjusted into place in the drill collar. Fig.

4 shows a portion of the shell or retainer and one of the blades of the bit, and gives a phantom outline of the principal parts and movement of these parts, in collapsing or expanding the blades of the bit. Fig. 5 shows the stem, with center blade of the bit attached to the lower part thereof, to which stem is attached and suspended, the mechanical devices used in the adjusting, expanding, and collapsing of the outer blades of the bit. Fig. 6 shows another view of the bit and stem. Fig. 7 shows an enlarged view of the upper part of Fig. 1, known as the packer, with fishing tool inserted, ready to be pulled to the surface. Fig. 8, another view of the outside blades of the bit. Fig. 9, broken view of packer and fishing tool. Fig. 10, inside half of shell or retainer, with guide slot. Fig. 11, another view of packer. Fig. 12, detached view of hanger connecting piece at lower end and connection bar above. Fig. 13 shows sprung lock. Fig. 14 shows a cross section view of the stem and shell or retainer, at the point indicated by the dotted line. Fig. 15 shows a cross section view of the stem and shell or retainer, at the point indicated by the dotted line. Fig. 16 shows a bottom plan view of the device as shown in Fig. 2.

The process of boring is accomplished by screwing fast a length of pipe or drill tube to the upper end of drill shell or retainer with all its inherent parts locked intact, and boring continuous down, screwing fast other lengths of pipe or tube until such a time as blades are to be renewed or sharpened. In connection with this structure I provide a member movably attached to the drill mechanism which member can be removed when the drill mechanism is in proper position within the drill shell. When it is necessary to repair the drill mechanism, this member is inserted into the drill tube and can be attached to the drill mechanism in such a manner that such mechanism can then be collapsed and removed from the drill tube to the surface of the ground for such repairs or inspection as is needed and then be again lowered to the bottom of the drill tube and into the drill retainer or shell at the lower end thereof. The collapsed bit is lowered to the drill shell or retainer until latches (*i*¹) engage the guides (*j*) which guide them to their proper places, allowing latches (*i*¹) to expand, thus releasing latches ¹⁰⁰ ⁹⁰ ⁹⁵ ¹⁰⁵ ¹¹⁰

(*i*²) thus releasing the stem (*c*), and lowering the lifters (*g*¹). The weight of the blades (*a*) is now shifted from the lifters (*g*¹) to the hangers (*g*), allowing the blades (*a*) to gravitate, and be pushed into position as the blade (*b*) is lowered to its proper place. Latches (*i*³) can only expand into recess (*j*¹) when the blades are in working position. When latches (*i*³) are expanded, they release the packer (*e*), allowing it to be forced down, thereby expanding the rubber ring (*e*¹) at the same time bringing disengaging nut (*o*) in contact with the water pipe (*l*), forcing the fishing stem (*r*) up into the fishing tool, pulling in dogs (*q*), thereby releasing fishing tool, which is pulled to the surface leaving bit in place for drilling. Blades (*a*) are held firmly in position and reinforced by shoulders thereof fitting into slot (*m*) in drill retainer or shell.

When the bits (*a*) and (*b*) are to be changed, the engaging nut (*o*¹) is placed instead of nut (*o*), on the fishing tool stem (*r*), and lowered into and through the drill pipe, until nut (*o*¹) comes in contact with spring (*p*), releasing spring (*p*) from recess (*t*¹). The dogs (*q*) expand and come into contact with recesses (*t*), thereby connecting fishing tool to packer. The packer is raised until slide blocks (*n*) come into contact with top of slot (*s*³), thereby allowing rubber ring (*e*¹) to contract, and at the same time releases latches (*i*³). The stem (*c*) is now raised. The stem (*c*) continues to be raised until lugs (*w*) come into contact with ledges (*w*¹) in lifter slot (*s*¹), which raises lifter (*g*¹), (the lifters (*g*¹) are composed of two parts suitably hinged together, thereby raising and folding the blades (*a*) into collapsed position, with the guidance of connecting pieces (*h*¹), which are thrown at right angles from hangers (*g*). The latches (*i*²) are then allowed to pull into slot (*s*⁶), which releases latches (*i*¹) from slots (*s*⁵) at the same time bar (*h*²) which connects the hangers, comes into contact with the bottom of slot (*s*²). The structure is then entirely released and ready to pull to the surface.

50 NOTE 1.—The slide blocks (*n*) are recessed into slots (*S*⁴) of packer piece (*e*).

NOTE 2.—(*L*¹) shows water course and (*p*¹) shows spring which holds fishing tool stem raised, thereby holding dogs in collapsed position, when desired.

Having thus described my patent, what I claim as new, and desire to secure by Letters Patent, is:

60 1. The combination with a retaining shell, of a stem movable through the shell, hangers carried by the stem, bits flexibly connected with the hangers, means whereby the hangers may be placed in stationary position with respect to the shell, said stem being movable with respect to the hangers and

adapted to move between the bits to extend same when the hangers are held stationary, as described.

2. The combination with a retaining shell, of a stem movable through the shell, hangers 70 slidably mounted on the stem, expandable bits suspended on the hangers, means for fixing the hangers stationary within the shell, said stem being movable between the bits to expand and hold them expanded 75 while the hangers are held stationary, as described.

3. The combination with a retaining shell, of a stem movable through the shell, hangers 80 slidably disposed on the stem, bits flexibly engaged with the hangers, lifters on the stem arranged to normally hold the bits in folded position, means on the hangers engageable with the stem to hold the stem in predetermined position while the bits are suspended 85 on the lifters, means on the hangers engageable with the shell to hold the hangers in fixed position and to release the stem whereby it can gravitate to move between the bits to expand and hold same expanded while 90 the hangers are held stationary, as described.

4. The combination with a retaining shell, of a stem movable through the shell, hangers 95 slidably mounted on the stem and provided with engaging means for holding the stem in predetermined position with respect to the hangers, bits flexibly connected with the hangers, lifters mounted on the stem and engageable with the bits to hold same in folded position when the stem is held engaged with the hangers, means for holding the hangers stationary within the shell and to release the stem, the stem being arranged to gravitate to release the bits from suspension on the lifters and to allow the stem to move between the bits, as described.

5. The combination with a retaining shell, of a stem movable through the shell, hangers 100 slidably mounted on the stem, bits, links connecting the hangers with the bits, lifters on the stem flexibly connected with the bits and arranged to pull the bits into folded position, means on the hangers engageable with the stem to hold the stem fixed stationary with respect to the hangers when the bits are in such folded position, means on the hangers engageable with the shell to hold the hangers stationary with respect to the stem and to release the stem from engagement with the hangers, said stem being arranged to gravitate to release the bits from the suspension on the lifters and to allow the stem to move between and expand the bits, as described.

6. The combination with a retaining shell, of a stem movable through the shell, hangers 105 slidably disposed on the stem, bits, links connecting the hangers and the bits, lifters

- on the stem, links connecting the lifters with the bits, means on the hangers engageable with the stem to hold it in a lifted position, means on the hangers engageable with the 5 shell to hold the hangers stationary with respect to the stem and to release the stem from engagement with the hangers to allow the stem to have movement with respect to the hangers, as described.
- 10 7. The combination with a retaining shell, of a stem movable through the shell, expandable bits carried by the stem and arranged to expand when projected below the shell, a packer movable through the upper 15 end of the stem, the upper end of the stem being provided with an annular groove, a resilient ring normally disposed adjacent said groove, means normally holding the packer away from said ring until the bits are expanded, said means being released 20 after the expanding of the bits to allow the packer to be moved against the ring to force it into said groove, as described.
- In testimony whereof, I have affixed my signature in the presence of the two wit- 25 nesses.

HARRY D. HAMPTON.
